UNITED STATES PATENT OFFICE.

ROBERT L. PRAHAR, OF BROOKLYN, NEW YORK.

BAG FRAME.

1,403,864.

Specification of Letters Patent. Patented Jan. 17, 1922.

Application filed June 30, 1921. Serial No. 481,512.

To all whom it may concern:

Be it known that I, ROBERT L. PRAHAR, a citizen of the United States, and resident of Brooklyn, in the county of Kings and State 5 of New York, have invented certain new and useful Improvements in Bag Frames, of which the following is a specification.

This invention is an improvement in frame or jaw constructions for ladies' handbags 10 although possibly adaptable for use in pocketbooks and other package or article carriers.

My invention involves improvements in the fastening means, the handle attaching 15 means and the provision of a separate and smaller article carrier within the main bag or receptacle. My invention is adapted for use with the ordinary type of bag jaws or frames including pivotally connected members 20 each substantially U-shaped in cross-section. It includes as the essential feature the use of a separate plate or frame member mounted between the two main frame members and having certain special features 25 hereinafter referred to.

In the accompanying drawings,

Fig. 1 is a side elevation of a device constructed in accordance with my invention, minor portions being broken away,

30 Fig. 2 is a top edge view; and;

Fig. 3 is a transverse section on the line 3—3 of Fig. 1.

I have illustrated only the bag jaw or frame, the body of the bag being omitted. 35 This body portion may be of fabric, leather or any other suitable material and of any desired form or construction.

The frame includes two main frame members 10 and 11 pivotally connected by rivets 40 or pivot pins 12, each member substantially channel-shaped in cross-section so as to form a groove or channel 13 in which the edge of the body of the bag may be secured. As the important feature of my invention, I 45 provide a third frame member 14 mounted between the two frame members 10 and 11. Although this intermediate or auxiliary frame member may be also secured to the pivots 12, it preferably terminates at a short 50 distance from them as indicated at the bottom of Fig. 3 and is rigidly and permanently secured to one of the main frame members, for instance, the member 11. The auxiliary frame member 14 is cut to follow the general 55 outline of the main frame members but projects outwardly beyond the latter at one

or more points along its length. Preferably it has projecting portions 15 which may have apertures therethrough serving for the attachment of a suitable handle. At the central point it may have a projecting portion 16 adapted to cooperate with or form a part of the fastening device for normally holding the two main members together. As shown this projecting portion 16 has an aperture 17 through which may extend the combined catch and finger piece 18 of a short spring arm 19 carried by the frame member 10. In closing the bag the catch 18 passes through the aperture and binds against the 70 edge of one wall thereof, so as to hold the main members together but the frame may be conveniently opened by pressing outwardly on the part 18 while gripping it and the opposite side of the portion 16 between 75 the thumb and finger.

It will be noted that the two handle attaching portions as well as one member of the snap fastener are integral with the auxiliary frame member 14. This involves a reduction 80 in the cost of assembly. It is merely necessary to solder the auxiliary frame member to the member 11 instead of separately attaching the parts serving the function of the three parts 15 and 16. As these are integral, 85 there is little or no liability of their becoming loosened or accidentally broken off or bent out of place. Only two members thus have to be secured to the main frame namely, the members 14 and 19 as against the attaching 90 of four members in the ordinary construction.

The member 14 also has an inwardly projecting flange or portion 20 which serves as a small interior article carrier. The flange 95 may be stamped to form a chamber 21 or may be perforated and a shallow chamber soldered or brazed thereto. Below the chamber there may be a projecting portion to which may be hinged a cover plate 21. The receptacle and cover are shown as connected by a pivot pin 23 and a coil spring 24 normally tending to hold the cover closed.

I do not wish to be limited to the specific form or purpose of this receptacle or article 105 carrier as it may be of such shape as to serve the purpose of a small coin purse or may carry a powder puff, lip stick or other toilet articles. The outer surface of the cover may carry a small mirror if desired. It will be 110 noted that this receptacle or article carrier is normally entirely concealed within the

body of the bag and is rigid with the frame of the bag so as to be held in a definite rigid position when the bag is open rather than freely suspended within the bag as is the case in some constructions. The device is inexpensive to manufacture, as the forming of the receptacle, the handle attachments and the catch may be accomplished by a single stamping operation.

10 Having thus described my invention, what I claim as new and desire to secure by Letters-Patent of the United States is:—

15 1. A bag frame including a pair of pivotally connected body carrying members and an intermediate member substantially following the contour of the main frame members and having an inwardly projecting integral receptacle carrying part.

20 2. A bag frame including a pair of pivotally connected body carrying members and an intermediate member substantially following the contour of the main frame members and having an inwardly projecting integral receptacle carrying part provided 25 with a hinged cover.

30 3. A bag frame including a pair of pivotally connected frame members, each substantially channel-shaped in cross-section to receive the edges of the body of the bag and an intermediate frame member having an outwardly projecting portion serving as a catch part for holding the main frame members together and having an inwardly projecting part serving as an article receptacle.

35 4. A bag frame including a pair of pivotally connected frame members, each substantially channel-shaped in cross-section to receive the edges of the body of the bag and an intermediate frame member having outwardly projecting portions serving as handle attaching parts and having an inwardly projecting part serving as an article receptacle.

45 5. A bag frame including a pair of main frame members pivotally connected and adapted for connection thereto of the walls of the bag and an intermediate plate disposed in a plane between said frame members with its outer edge approximately following the outer edges of said frame members having apertured portions projecting beyond the outer edges of the main frame

members for the attachment of a handle and having a body portion disposed inwardly from the inner edge of said main frame members and carrying an article receptacle. 55

6. A bag frame including a pair of main frame members pivotally connected and adapted for connection thereto of the walls of the bag and an intermediate plate disposed in a plane between said frame members and extending approximately along the length of said members and having apertured portions projecting beyond the outer edges of the main frame members for the attachment of a handle and having a body portion disposed inwardly from the inner edge of said main frame members and carrying an article receptacle provided with a pivoted cover. 60

7. A member adapted for attachment to a pair of pivotally connected bag frame members and comprising a stamped metal plate including a receptacle adapted to be disposed within the bag, handle attaching parts and a catch projecting outwardly from said main frame members. 70

8. A plate adapted to be secured to the inner surface of one member of a pair of pivotally connected bag frame members and including an integral portion provided with a receptacle and a pivoted cover. 75

9. A plate adapted to be secured to the inner surface of one member of a pair of pivotally connected bag frame members and including an integral portion provided with a receptacle and a pivoted cover and integral portions extending in the opposite direction from the attached main frame member and serving for the attachment of a bag handle. 85

10. A plate adapted to be secured to the inner surface of one member of a pair of pivotally connected bag frame members and including an integral portion provided with a receptacle and a pivoted cover, and an integral portion extending outwardly in the opposite direction from the main frame member and serving as a portion of a catch for holding the main frame members together. 90

Signed at New York, in the county of New York and State of New York, this 28th day of June, A. D. 1921.

ROBT. L. PRAHAR.
